ABSTRACT

The invention contemplates employment of plural preset comparators, such as flip-flop set to trigger at different reference-voltage levels, to accurately identify and quantize discrete voltage levels in the electric-signal wave form by which displacement increments are tracked, or picked off, for measurement. The fast change of state in each of the elements of such a device makes possible the prompt, accurate and unambiguous identification of each particular displacement increment. The described device is inherently applicable to digital encoding for remote transmission, and several embodiments are described.

INTERPOLATION MEANS FOR DISPLACEMENT MEASUREMENT

This invention relates to an arrangement for interpolation of periodic electric signals dependent on displacement, whether longitudinal or angular.

In the measurement of displacement or of angle, it is presently general practice, for reasons of objectifying the measuring results, to digitally indicate or further process the measured values.

Measuring arrangements of the type indicated generally involve linear measuring systems or angle pickoffs which supply periodic electric signals in accordance with the change in displacement or angle.

In order to be able to recognize the direction of the measuring action, it is general practice in such measuring arrangements to at least generate two phase-shifted signals.

For increasing the resolving power of these measuring arrangements, it is prior art to subdivide the periodic length of the signals dependent on displacement and angle, respectively, i.e., to interpolate electrically.

However, various methods of the hitherto used interpolation methods suffer from the shortcoming that they are not independent of the amplitudes of the signals supplied, or they are also susceptible to changes in phase of the input signals. Moreover, it is prior art to attain an interpolation by a doubling of frequency of the input signals and subsequent triggering of their zero passages. However, the interpolation factor attainable thereby is relatively small.

Furthermore, it is prior art to interpolate displacement-measuring signals indirectly via a saw-tooth voltage dependent on time which is compared with a number of fixed voltages. However, this prior method is dependent on very fine divisions and a uniform course of movement, respectively, in the measuring operation.

It is an object of the present invention to avoid the above-described disadvantages, and to attain a more far-reaching interpolation, with relative economy.

According to the invention, the foregoing objects are attained by providing that the signal dependent on displacement (whether lineal or angular), and being interpolated, is passed through a number of comparators ($K_1, K_2, \dots$) of different trigger levels ($U_{R1}, U_{R2}, \dots$), and the trigger levels are adapted to the given signal waveform and to the respective signal amplitude, such that after each given interpolation step (ΔS) there is a sudden change in the output voltage ($U_A, U_B, \dots$) across at least one comparator output.

The adaptation of the trigger levels to the instantaneous amplitude of the interpolating signal is effected either by stabilizing the amplitude itself or by re-setting the trigger levels.

Preferably, this is controlled via a reference signal dependent on the input signal amplitude, and when using several phase-shifted signals, also on the changes in phase. The reference signal can be derived from the pickoff of the measuring system itself or can be generated from the phase-shifted measuring signals supplied to the interpolator.

Further details, features and objects of the invention will be pointed out or will occur to those skilled in the art from a reading of the following specification, in conjunction with the accompanying drawings.

In said drawings:

FIG. 1 is an electrical block diagram schematically showing elements of an interpolation circuit of the invention;

FIGS. 2a, 2b and 2c are graphical displays of waveforms at different parts of the circuit of FIG. 1, said displays being for voltage U as a function of displacement S to be interpolated;

FIG. 2d is a code display applicable to the functional operation of the interpolation circuit of FIG. 1;

FIG. 3 is a circuit diagram of logic-circuit means constituting a part of the circuit diagram of FIG. 1;

FIG. 4 is a further graphical display of voltage U as a function of displacement S ;

FIG. 5 is a block diagram similar to FIG. 1, to illustrate a modification;

FIGS. 6a, 6b and 6c are displays corresponding to those of FIGS. 2a, 2b and 2d but applicable to the circuit of FIG. 5; and FIG. 7 is a simplified block diagram to illustrate a further modification.

Signal voltages U_1 and U_2 are supplied at interpolator inputs E_1 and E_2 (FIG. 1), the signals U_1 and U_2 being generated by pickoff means (not shown) forming part of displacement or angle-measuring means of known construction. The signals U_1, U_2 are in quadrature (i.e., 90° phase-displaced) and sinusoidal, each covering a full cycle for a full unit of displacement S to be measured, as for example a full single rotation of a shaft, it being understood that repeated cycles of the shaft rotation (or other unit of displacement) are counted by other means, not shown. In a first signal-processing circuit I, signals U_1, U_2 are rectified by full-wave rectifiers 11, 12, to produce voltages U_3, U_4 across their outputs (see FIG. 2a); a second signal-processing circuit or reference-signal generator II will be later described. The two signals U_3, U_4 are summed in an adding stage A_1 , to produce a triangle-shaped signal U_5 in known manner (see FIG. 2a). The signal U_5 has double the amplitude of either signals U_3, U_4 ; it also has twice as many intercepts of the zero- U axis, and these intercepts are phase-displaced 45° with respect to those of the input signals U_1, U_2 . The signal U_5 may thus be effectively a frequency-doubled signal, and will be so termed.

The input signals U_1, U_2 and the frequency-doubled signal U_5 obtained therefrom are applied to the inputs of a number of comparators $K_1, K_2, K_3, K_4, K_5, \dots, K_{11}$, as for example flip-flops of known construction; the nature of these comparator circuits is to cause sudden change in a particular comparator-output voltage ($U_A, U_B, \dots, U_L$) when and if the applied-signal voltage (U_1, U_2 or U_5 , as the case may be) passes through the magnitude corresponding to the trigger-voltage level for the corresponding particular comparator-reference input setting. The reference-input connections of comparators K_1, K_2, K_3 are all grounded; hence, their trigger-voltage level is equal to zero. The trigger-voltage levels are designated $\bar{U}_{R1}, \bar{U}_{R2}, \bar{U}_{R3}, \bar{U}_{R4}$, respectively, for comparators K_4, K_5, K_6, K_7 , and are designated $U_{R1}, U_{R2}, U_{R3}, U_{R4}$, respectively, for comparators K_8, K_9, K_{10}, K_{11} .

The trigger-voltage levels for comparators K_4 to K_7 are supplied from a first voltage divider comprising a resistor chain R_1, R_2, R_3, R_4 , and trigger-voltage levels for comparators K_8 to K_{11} are supplied from a second voltage divider comprising a resistor chain R_5, R_6, R_7, R_8 . These resistor chains are in turn supplied by reference voltages $\bar{U}_R$ and U_R , respectively, as will later be more fully described.

Each resistor chain is preferably designed to establish regulator measurement intervals of the displacement or angle S , depending upon the nature of the signal waveform being interpolated; thus, the trigger-voltage levels at connection points along each chain establish output-voltage changes in the respective comparators at regular intervals, corresponding to equal changes in the displacement or angle S . Since in the form shown the signal U_5 (being interpolated) has the form of an isosceles triangle, all resistors $R_1, R_2, \dots, R_8$ are of equal magnitude; it will be understood, however, that by suitable selection of elements in each resistor chain, any particular signal waveform can be accommodated as long as it is not characterized by any infinite slopes, such as for example sudden change from zero to maximum positive or to maximum negative.

To illustrate the indicated trigger-voltage relationship, reference is made to FIG. 4, in which plural trigger-voltage levels U_{Rn} and U_{Rb} , respectively, are shown for a triangular waveform A and for a sinusoidal waveform B, in conjunction with pre-established interpolation steps or increments ΔS . The resistor chain must be stepped in the same ratio as the corresponding trigger-voltage levels.

For example, if the signal level is increased, thereby altering the signal waveform A by an increase in amplitude to that shown at A' (dashed lines), all pre-established trigger levels must be reset to values indicated by primed notation (e.g.,

U'_{R_0}) if triggering is to be effected at the same displacement points s . It follows that the trigger levels must assume different values with changes in amplitude of the interpolating signal if the initiation of the interpolation signals is to be effected at the same points s .

The signal-processing circuit II (FIG. 1) illustrates how the respective trigger levels can be correctively reset, for changes in amplitude and phase of the interpolating signal, by providing a reference signal U_R .

In circuit II, the input signals U_1 and U_2 are supplied to another adding stage A_2 . By the addition of these two input signals, an output signal is obtained in known manner having the same frequency as the input signals U_1 and U_2 , however, being shifted in phase by -45° and having an amplitude greater by the factor $\sqrt{2}$. Stage A_2 includes means for attenuating the added resultant of signals U_1 , U_2 , to the extent of the factor $\sqrt{2}$, and its output is supplied to a full-wave rectifier 14, to produce the rectified positive signal U_{10} (see FIG. 2c). In a separate line, the input signal U_2 is inverted by means of an inverter stage I_2 and added to the input signal U_1 in another adding stage A_3 , thereby producing a signal of amplitude greater by the factor $\sqrt{2}$, and of the frequency of the input signals U_1 and U_2 , respectively, but shifted in phase by $+45^\circ$ with respect to signal U_1 ; this signal, attenuated by the factor $\sqrt{2}$ of the adding stage A_3 , is supplied to a full-wave rectifier 13 across the output of which the positive signal U_9 is obtained (see FIG. 2c). The positively rectified half-waves of the signals U_9 and U_{10} are supplied to a fourth adding stage A_4 , together with the signal U_4 and together with the signal $\bar{U}_3$, the latter being the signal U_3 after inversion in an inverter stage I_1 . The addition of these four signals is represented by the reference signal U_R (see FIG. 2c) which is proportional to the amplitudes of the input signals U_1 and U_2 .

By an appropriate attenuation of the reference signal U_3 the modulation or ripple obvious from FIG. 2c can be made almost ineffective. Besides, the modulation can substantially be decreased, to practically no significance, by doubling the number of phase-shifted half-wave signals supplied to the adding stage A_4 . Test results establish, for example, that with $\pm 90^\circ$ phase shifts of the two input signals U_1 and U_2 , the reference signal U_R (FIG. 2c) adapts to the signal U_5 being interpolated (FIG. 2a), and that the interpolation arrangement operates correctly up to almost 0° phase shift.

As already noted, the references voltage U_R is applied across one resistor chain R_5 , R_6 , R_7 , R_8 , and after inversion at an inverter stage I_3 it is also applied across the other resistor chain R_1 , R_2 , R_3 , R_4 ; the inverted reference voltage is designated $\bar{U}_R$. It will be seen that the trigger levels U_{R1} , U_{R4} and $\bar{U}_{R1}$, $\bar{U}_{R4}$, connected to the respective reference inputs of the comparators K_4 , K_{11} , necessarily follow or track the reference signal U_R (and $\bar{U}_R$), in both amplitude and phase, and that the described circuits also correctly follow amplitude and phase variations of the signals being interpolated.

FIG. 2b illustrates, on the same displacement base as FIG. 2a, the changes in state of flip-flops K_1 to K_{11} in the course of a full cycle of displacement S . For example, the flip-flop K_1 , which is connected to directly track the input signal U_1 , with respect to zero-volts (ground) reference, produces an output voltage U_L which is characterized by one state for the first half of the U_1 cycle and by its other state (zero-volts output) for the second half of the U_1 cycle. In like manner, flip-flop K_2 , which is connected to track the other input signal U_2 (90° phase-displaced from U_1), produces an output voltage U_K similar to U_L but 90° phase-displaced therefrom. The other flip-flops or comparators are shown to produce analogous output voltages U_A , U_B , ..., U_L , dependent on change of state determined when the interpolating signal U_5 traverses each of the predetermined trigger-voltage levels.

FIG. 1 shows that the described signal-sequencing voltages U_4 , U_B , ..., U_L , originating through action of the comparator or flip-flop elements K_1 ..., K_{11} , may be supplied to logic circuit means LS_1 of known type, whereby voltages U_6 and U_7 (see FIG. 2b) are obtained at the respective output terminals A'_1

and A'_2 . An illustrative logic circuit LS_1 , shown in FIG. 3, is seen to substantially comprise plural inverter stages and NAND-elements; since the circuit is conventional, it need not be described other than by legend identification of the input-voltage connections U_A , U_B , ..., U_L and of the voltage-output terminals at which voltages U_6 and U_7 are produced.

The phase displacement or side spacing Δs of the voltages U_6 and U_7 (FIG. 2b) is smaller by the interpolation factor (here 40) than the full period of the input signals U_1 and U_2 . This displacement between signals U_6 and U_7 is 90° to enable correct counting with respect to their sign, in connection with a known bidirectional counter (not shown) having a quartering logic.

If the interpolation steps are not to be counted but rather are to be encoded, as for remote transmission, it will be understood that, in place of the logic circuit LS_1 , a known encoding network may be operated according to the code indicated in FIG. 2d, reflecting the pattern of the changing flip-flop states O and L , noted as voltage levels in FIG. 2b. Thus encoded, a fixed digital value can be associated with each interpolation value Δs . The embodiment according to FIG. 1 is thus seen to generate 40 different fixed values (see FIG. 2b) for each cycle of displacement S to be measured.

FIG. 5 illustrates another interpolation arrangement according to the invention, using some of the same structural elements as the arrangement according to FIG. 1; like parts are therefore referenced by the same reference numerals in both Figures. However, in the embodiment according to FIG. 5, the first signal-processing means is modified (identified I'), in that the signal U_5 originating from the adding stage A_1 is supplied to a full-wave rectifier 15, thus generating a signal U_{11} (see FIG. 6a) the frequency of which is doubled with respect to U_5 , but which is characterized by the same number of intercepts of the zero-U axis as in the case of voltage U_5 . In the circuit of FIG. 5, the signal U_{11} is applied at one respective input of the comparators (e.g., flip-flops) K_4 , K_5 , K_6 and K_7 . However, the same circuit II of FIG. 1 will be recognized, to obtain the reference signal U_R from the addition of signals $\bar{U}_3$, U_4 , U_9 and U_{10} . In the embodiment of FIG. 5, the signal U_R need not be negated (inverted), since the signal U_{11} is only positive, as can be seen from FIG. 6a. The reference signal U_R is again subdivided by means of the resistor chain R_5 , R_6 , R_7 and R_8 so that when using any desired signal U_{11} (with the restriction already made, and with the aid of comparators), sudden changes in the comparator output voltages (e.g., changes in flip-flop state) occur at regular intervals (see FIG. 6b).

In the example illustrated in FIG. 5 in which the input signals U_1 and U_2 , respectively, are to be subdivided into 40 parts, a quasi-triangular function has again been assumed, calling for a resistance ratio of 1:1; thus, $R_5 = R_6 = R_7 = R_8$. The reference voltages U_{R1} , U_{R2} , U_3 and U_{R4} are applied to the second input of the comparators K_4 to K_7 . The signals U_1 , U_2 and U_3 are triggered by means of the comparators K_1 , K_2 and K_3 , as these voltages traverse or attain the zero-U axis. The output signals of the comparators K_1 to K_7 , namely, U_E , U_G , U_F , U_A , U_B , U_C and U_D , may be supplied to appropriate logic-circuit means LS_2 in known manner so that signals U_{12} and U_{13} (shown in FIG. 6b) are obtained across the outputs A'_3 and A'_4 , respectively.

The embodiment of FIG. 5 also lends itself to the encoding of fixed values associated with the interpolation steps within a period or a part of a period. To this end, the logic-circuit LS_2 may be replaced by a known encoding network operating according to the code of FIG. 6c.

It will be evident that the arrangement shown in FIG. 5 is distinguished by a substantially reduced number of circuit elements (comparators). It will be further understood that the invention is not bound to the embodiments shown hereinbefore, but that numerous variants can be realized within the scope and nature of the invention. Thus, by way of example, instead of causing the trigger levels to follow via a reference signal, the amplitude of the input signals can be maintained constant,

as for example using the same reference signal, as illustrated in FIG. 7. Herein, the input signals U_1 and U_2 are first passed through amplifiers V_1 , V_2 of variable amplification, the gain of which is controlled via a reference-signal generator meeting the description of the structural element II of FIG. 1.

The input signals U_{C1} and U_{C2} , respectively, thus maintained constant, are then processed further, as already shown, with the difference that now a fixed d.c. voltage can be applied across the resistor chains.

It is also possible to obtain the reference signals (dependent on amplitude) directly from the pickoff, as in the case of a photoelectric pickoff from the intensity of a light source operated by picked-off voltage.

What is claimed is:

1. Means for interpolation of continuously varying periodic electric signals of amplitude dependent upon displacement, comprising a plurality of comparators each having an input trigger-level connection and an input control connection, displacement-responsive reference-voltage means including voltage-dividing means with plural taps each continuously connected to the input trigger-level connection of a different comparator whereby each comparator is capable of output change in accordance with a different input voltage, and means continuously connecting a periodic electric signal in common to the control inputs of a plurality of said comparators, whereby in the course of periodic variation of the electric signal said comparators are caused to change their output states in a succession corresponding to the electric signal change, so that such changes in output states directly reflect displacement change.

2. Means according to claim 1, in which said comparators are flip-flops.

3. Means according to claim 1, in which said connecting means includes means for maintaining constant the amplitude of the signal being interpolated.

4. Means according to claim 1, in which said reference-voltage means includes an input control connection referenced to the amplitude of the electric signal being interpolated.

5. Means according to claim 4, in which said voltage-dividing means comprises a chain of resistors.

6. Means according to claim 1, in which said periodic electric signal comprises at least two phase-displaced signals dependent on displacement, and in which said reference-voltage means includes input means connected for concurrent response to both said phase-displaced input signals.

7. Means according to claim 1, in which said periodic electric signal comprises at least two phase-displaced signals dependent upon displacement, said connecting means comprising means combining both said phase-displaced signals prior to supply to said comparators.

8. Means according to claim 7, in which said signals are 90° phase-displaced and in which said last-defined means com-

bines said signals to produce a succession of triangular waveforms.

9. Means according to claim 8, in which said voltage-dividing means comprises plural taps at equal voltage increments, whereby displacement increments identified by comparator action may be correspondingly equal.

10. Means for interpolation of periodic electric signals dependent upon displacement, comprising a plurality of comparators each having an input trigger-level connection and an input control connection, reference-voltage means including voltage-dividing means with plural taps each connected to the input trigger-level connection of a different comparator whereby each comparator is capable of output change in accordance with a different input voltage, and means connecting a periodic electric signal in common to the control inputs of a plurality of said comparators, said periodic electric signal comprising at least two 90° phase-displaced signals dependent upon displacement, said connecting means comprising means combining both said phase-displaced signals in triangular waveform prior to supply to said comparators, whereby in the course of periodic variation of the electric signal said comparators are caused to change their output states in a succession corresponding to electric-signal change, said taps being at equal voltage increments, whereby displacement increments identified by comparator action may be correspondingly equal, and said reference-voltage means including input means connected for concurrent response to both said phase-displaced input signals, whereby amplitude variation in the resultant of said phase-displaced input signals is neutralized in the successive triggering of said comparators:

11. Means for interpolation of periodic electric signals dependent upon displacement, comprising a plurality of comparators each having an input trigger-level connection and an input control connection, reference-voltage means including voltage-dividing means with plural taps each connected to the input trigger-level connection of a different comparator whereby each comparator is capable of output change in accordance with a different input voltage, and means connecting a periodic electric signal in common to the control inputs of a plurality of said comparators, said periodic electric signal comprising at least two phase-displaced signals dependent upon displacement, said connecting means comprising means combining both said phase-displaced signals prior to supply to said comparators, whereby in the course of periodic variation of the electric signal said comparators are caused to change their output states in a succession corresponding to electric-signal change, and said reference-voltage means including input means connected for concurrent response to both said phase-displaced input signals, whereby amplitude variation in the resultant of said phase-displaced input signals is neutralized in the successive triggering of said comparators.
